(57) **CLAIM**

The ornamental design for spoke, as shown and described.

DESCRIPTION

FIG. 1 is a perspective view of the spoke showing my new design;

FIG. 2 is another perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.

The spoke is shown on a reduced scale in FIGS. 3-8.

The broken away symbols in the drawings indicate that the appearance of any portion of the article between the break lines forms no part of the claimed design.
